UNITED STATES PATENT OFFICE.

JOHN B. MOFFAT, OF BRONXVILLE, NEW YORK, ASSIGNOR TO BIGELOW CARPET COMPANY, A CORPORATION OF MASSACHUSETTS.

DESIGN FOR A RUG.

43,632.

Specification for Design.

Patented Feb. 25, 1913.

Application filed January 17, 1913. Serial No. 742,729. Term of patent 7 years.

To all whom it may concern:

Be it known that I, JOHN B. MOFFAT, a citizen of the United States, residing at Bronxville, in the county of Westchester and State of New York, have invented a new, original, and ornamental Design for a Rug, of which the following is a specification, reference being had to the accompanying drawing, forming part thereof.

The drawing illustrates one quarter of a rug showing my new design, the remaining three quarters become duplicates thereof, when the one quarter shown in the drawing is reversed bi-symmetrically from the central axes, both horizontal and vertical.

I claim:

The ornamental design for a rug, as shown.

JOHN B. MOFFAT.
